US0D1111867S

(12) **United States Design Patent** (10) **Patent No.:** **US D1,111,867 S**
(45) **Date of Patent:** **** Feb. 10, 2026**

(54) **BOX MOUNTING ADAPTER**

(71) Applicant: **Orbit Industries, Inc.**, Los Angeles, CA (US)

(72) Inventor: **Kai Zhang**, Los Angeles, CA (US)

(**) Term: **15 Years**

(21) Appl. No.: **29/961,391**

(22) Filed: **Sep. 5, 2024**

(51) **LOC (15) Cl.** **08-05**

(52) **U.S. Cl.**

USPC **D8/381**; D13/154

(57) **CLAIM**

The ornamental design for a box mounting adapter as shown and described.

DESCRIPTION

FIG. 1 is a top perspective view of a box mounting adapter, showing our new design;

FIG. 2 is a front elevation view thereof;

FIG. 3 is a right side elevation view thereof;

FIG. 4 is a left side elevation view thereof;

FIG. 5 is a rear elevation view thereof;

FIG. 6 is a bottom view thereof; and,

FIG. 7 is a top plan view thereof.

The broken lines in the drawings illustrate portions of a box mounting adapter which form no part of the claimed design.

1 Claim, 5 Drawing Sheets
